(57) **CLAIM**

We claim the ornamental design of a pump and bearing
frame, as shown and described herein.

DESCRIPTION

FIG. 1 is a top back perspective view of a pump and bearing
frame according to some embodiments of the present invention;

FIG. 2 is a bottom front perspective view of the pump and
bearing frame shown in FIG. 1;

FIG. 3 is a side view of one side of the pump and bearing
frame shown in FIG. 1;

FIG. 4 is a corresponding side view of the other side of the
pump and bearing frame shown in FIG. 3.

FIG. 5 is a back view of the pump and bearing frame shown
in FIG. 1;

FIG. 6 is a front view of the pump and bearing frame shown
in FIG. 1;

FIG. 7 is a top view of the pump and bearing frame shown
in FIG. 1; and,

FIG. 8 is a bottom view of the pump and bearing frame
shown in FIG. 1.
